UNITED STATES PATENT OFFICE.

SVEN A. SIEURIN, OF GOTTERBORG, SWEDEN.

LIFEBOAT.

Application filed November 9, 1925, Serial No. 67,726, and in Sweden January 9, 1925.

My invention relates to life boats and more specifically to improved means and arrangements for swinging life boats on board ship out to lowering position. The main object is to simplify the operation and control to the end that the boats may be swung out to lowering position by the use of only a single rope operated by only one man. Another important feature is the provision of improved means for effecting stabilization of the boats when ready for embarkation.

The various features of my invention are shown incorporated in the structure illustrated on the accompanying drawing, in which:

Figure 1 is a plan view of a boat and its supporting davit structure showing the normal or swung-in position;

Figs. 2 and 3 are similar views showing intermediate positions of the boat;

Fig. 4 is a similar view showing the boat in swung-out position ready for lowering;

Figs. 5 and 6 are enlarged fragmentary views showing different positions of the operating rope relative to the boat;

Fig. 7 is a sectional view on line 7-7 of Fig. 5; and

Fig. 8 is a side elevational view showing a modified arrangement.

In the swung-in position shown in Fig. 1, the life boat 1 and the davits 2 and 3 which are mounted on the ship take the position shown, the operating rope 4 extending from an arm 5 on the davit 3 around the stern 6 and carried along the inwardly turned side of the life boat through an eye 8, which eye is detachably fixed to a boss 19 on the side of the boat, the rope extending through and resting in a fork 9 on the side of the

boat and being then carried around the stern 7 and through a sheave 10 to a capstan 15 or the like on the ship (Fig. 8). There are two stops 11 and 12 on the rope for coacting with the fork 9 and the eye 8, respectively.

Other accessories, such as tackles 20 for the lowering of the boat, are shown in Fig. 8.

With the above arrangement only one man is required for swinging out a boat to lowering position. After having the boat lifted from its support 17 by means of the tackles 20, it is necessary only to operate the rope 4 by applying a hauling power at the free end

of the same. Normally, the stop 11 abuts against the fork 9, so that when pull is applied to the rope, the rope section 4^a applies lateral pressure to the stern of the boat, so that the boat and the davit 2 are swung outwardly to the position shown in Fig. 2. This continues until the rope section 4^a leaves the stern. Thereafter, the pull on the rope will be exerted by the stop 11 against the fork 9 and the boat will be moved longitudinally forwardly and swung further outwardly at its stern end 7, such movement continuing until the stop 11 slides out of the fork, and this occurs as soon as the rope section 4^a assumes the angle α with respect to the boat side as shown in Fig. 6. As soon as released from the fork 9 the rope assumes the position shown by the dotted lines in Fig. 6 and pull on the rope will then be transmitted to the arm 5 on the davit 3, as shown in Fig. 3, and this davit is swung outwardly to carry the end 6 of the boat outwardly, the boat assuming the position shown in Fig. 4 as the arm comes practically into alignment with the rope. During swing of the davit 3 the stop 12 on the rope has moved into abutting engagement with the eye 8. This engagement of the rope with the boat will prop the boat against longitudinal swing. For preventing sidewise swing of the boat a rope (not shown) may be fixed to the outer gunwale of the boat and carried under the boat forward to a cleat on the ship deck, in a manner already well known. Thus, a single man by a single rope is enabled to readily and efficiently swing a life boat from its position on deck into a lowering position, in which position it will be steadily held.

Various modifications can be used without departing from the spirit of the invention. In Fig. 8 I show an arrangement in which the rope is manually released from the boat. In this arrangement a kevel or cleat 14 is detachably fastened to a fitting 19 on the gunwale of the boat and has the eye 8. The stop 11 on the rope, in this case, is preferably in the form of a coil or ring through which a cord or rope 13 is threaded with one end fixed to the cleat 14 and the other end detachably wound around the cleat. Then, when the rope is pulled, as by means

of the capstan 15, the rope section 4^a, together with the cord 13, will become stretched and exert lateral pressure against the stern 7 of the boat to swing it from its 5 position, shown in Fig. 1, to that shown in Fig. 2. Sufficient slack should be permitted in the rope between the stop 11 and the arm 5 to permit the small inward swinging movement of the stern 6 when the stern 7 is 10 started to be swung outwardly. After the boat has been swung from the position of Fig. 1 to that of Fig. 2, the cord 13 is manually released from the cleat 14 so that the rope will then be free to become stretched 15 its entire distance and exert pull on the arm 5 and thus continue the movement of the boat from the position of Fig. 2 to that of Fig. 3 and eventually that of Fig. 4. The stop 12 then comes into engagement with the 20 eye 8 and the boat is locked against swinging movement.

Instead of fastening the rope 4 to an arm 5 on the davit 3, the rope can be carried around the vertical part of the davit and 25 fixed to the gunwale of the ship or to the deck at the left. The boat stern 7 can then be swung out in the manner previously described and then the pulling power will be transmitted to cause the rope to exert lateral 30 pressure against the boat and the stern 6 so that the boat will be pressed outwardly over the shipboard. A single man with a single rope can with this arrangement swing out the life boat, but the davit 3 will probably 35 not turn outward completely and, therefore, the other arrangements previously described are more desirable.

The arrangement can easily be made such 40 that the rope for each life boat is operated by a common rope or chain applied along the ship or otherwise and actuated by a capstan, so that all the life boats can be simultaneously swung out. The arrangement is also applicable in such cases where several 45 lift boats are placed one above the other, one arm 5 being in this instance provided for each life boat.

Instead of using a fork 9 for co-operating 50 with the rope, other devices such as a crotch, or a hook, or a clamp, or an eye, could be used. The device could be so shaped that it would hold the rope or chain fast so long as the pull is tangential to the boat side, but to release the rope as soon as the rope tries 55 to move away from the boat side when traveling from the position shown in Fig. 2 to that of Fig. 3.

The rope could also be held fast by means 60 of twine which is strong enough to hold during the swinging-out movement of the boat end from its position shown in Fig. 1 to that of Fig. 2, but which would give to a stronger pull and break, so that the rope would be released to exert its pulling power 65 on the arm 5.

Having described my invention, I claim as follows:—

1. In combination, two davits, a life boat suspended between them, a rope removably fastened to the side of the boat with the rope parts extending around the respective ends of the boat, one end of said rope being fixed to one of said davits, a sheave provided at the vertical part of the second davit for receiving the other end of said rope, and 70 pulling means connected with such other end of the rope.

2. In combination, two davits, a life boat suspended between them, a rope fixed at one end to one of the davits, a capstan engaging the other end of said rope, a sheave fixed to the other davit engaging said rope between the first davit and the capstan, and a fastening device on the inboard side of the life boat removably attached to said rope. 80

3. In combination, two davits on board a ship, a life boat suspended between them, a rope fixed at one end to one of said davits, said rope extending along that side of the boat which is turned to the ship, a sheave 90 fixed to the other davit for receiving said rope, hauling means employed at the free end of said rope, a stop on said rope, and a fastening device on said boat removably engaging said stop. 95

4. In combination, two davits on board a ship, a life boat suspended between them, a rope fixed at one end to one of the davits, said rope extending along the inboard side of the boat, a sheave fixed to the other davit 100 to receive said rope, hauling means applied to the free end of said rope, a stop on said rope, a fastening device removably engaging said stop, an eye attachably supported at substantially the middle of the boat, and a stop on that part of the rope which is between the first davit and said eye, said eye being located so that it abuts the stop at the moment the life boat has swung out. 105

5. In combination, two davits on board a ship, a life boat suspended between them, an arm rigidly fastened to one of said davits and extending practically horizontally in a direction away from the other davit when the boat is in its swung-in or resting position, a rope fixed at one end to the free end of said arm, said rope extending along the inboard side of the boat, a sheave fixed to said other davit for receiving said rope, hauling means applied to the free end of said rope, a stop on said rope, and a fastening device removably engaging said stop. 110

6. In combination, two davits on board a ship, a life boat suspended between them, an arm rigidly fastened to one of said davits and extending practically horizontally in a direction away from the other davit when the boat is in its swung-in or resting position, a rope fixed at one end to the free end of said arm, said rope extending along the 115 120 125 130

inboard side of the boat, a sheave fixed to part of the rope which is found between the said other davit for receiving said rope, first davit and the eye, said eye being located hauling means applied to the free end of so that it abuts the stop at the moment the 10 said rope, a stop on said rope, a fastening life boat has swung out.

5 device removably engaging said stop, an In witness whereof, I hereunto subscribe eye detachably provided at approximately my name this 14th day of October, 1925.

SVEN A. SIEURIN.
